FLASHING

David D. Smith, Los Angeles, Calif.

Application April 16, 1946, Serial No. 662,481

8 Claims. (Cl. 103—26)

1

This invention relates generally to weather-proofing devices, and more particularly to flashing for buildings and the like.

Although the invention may be useful in various types of construction and the like, it has particular utility in connection with the roofs of buildings, for providing a weatherproof seal therefor, and the invention will therefore be described in connection therewith.

It is an object of the present invention to provide a device of this character that is simple in construction, easy to install and reliable in providing a protective seal for roofing on buildings.

Another object of the invention is to provide a device of this character wherein the flashing may be easily removed and replaced to permit re-roofing of the structure.

Still another object of the invention is to provide a device of this character wherein raw edges of the metal exposed to the weather is reduced to a minimum.

A further object of the invention is to provide a device of this character wherein the reglet of the device is so shaped that when installed in a wall of poured concrete it will be firmly imbedded in such concrete, and fluid, such as rain, will be prevented from entering the reglet.

A still further object of the invention is to provide a device of this character wherein vibration thereof will be negligible.

Further objects and advantages of the invention will be brought out in the following part of the specification.

Referring to the drawings, which are for illustrative purposes only,

Fig. 1 is a sectional perspective of a flashing reglet embodying the present invention, said reglet being shown as installed in a masonry wall;

Fig. 2 is a sectional perspective showing the entire assembly of the weatherproofing device embodying the present invention;

Fig. 3 is a perspective view of anchoring clips which are used in the device; and

Fig. 4 is a sectional perspective of the flashing strip.

Referring to the drawings, there is shown a vertical concrete wall, indicated generally at 10. The present weatherproofing device includes a reglet member and a flashing member. The reglet, as shown in Figs. 1 and 2, comprises a strip of sheet metal, which may be copper, galvanized iron, or the like, and which is formed to provide a substantially triangular recess 11. The recess is defined by a substantially horizontal upper wall or panel 12, and a downwardly and outwardly

inclined lower wall or panel 13, the reglet being turned on itself at 14 to provide an inverted substantially U-shaped vertical upstanding flange 15. The arms of the U are spaced apart in close proximity to each other and are connected to the respective walls or panels 12 and 13. At the outer edge 12a of the wall 12 there is a downturned flange 16, a part of the free edge portion of which is turned back at 17 into contact with the inner side of said flange 16 to protect the raw edge 17a thereof from rain or the like. The flange 16 partially encloses the recess 11 along its upper outer side, and the outer face of said flange is substantially flush with the adjacent outer surface of the concrete wall 10. At the outer edge 13a of the recess wall 13 there is a downturned or depending flange 18, the outer surface of which also is substantially flush with the adjacent outer side of the wall 10 when the device is installed.

The assembly includes a plurality of longitudinally spaced anchoring strips indicated generally at 19, each of which has a laterally turned flange 20 which is received between the arms of the U-shaped lip 15 of the reglet. Each anchoring strip includes a portion 21 which extends from the flange 20, downwardly and outwardly of the recess 11, and a portion 22 which is upturned about the lower edge 16a of the flange 16 prior to the installation of the flashing strip, which is indicated generally at 25.

The flashing strip is also formed of sheet metal and is in the general shape of a T, there being a generally vertical flange or leg 26, a laterally extending portion 27 adjacent the top of the leg 26, and a top section 28 which is formed by bending the strip at 29 back over the laterally extending portion 27 with the adjacent surfaces of the parts abutting each other, the section 28 however being of substantially greater width than the portion 27. The leg 26 also includes a free edge portion or lip 30 which, when the flashing is installed, is slightly bent toward the adjacent upturned edge portion 31 of the roofing material 32 which is laid on the roof deck 33, the free edge of said lip forming a straight line contact with said edge portion 31 of the roofing material.

If desired, reinforcing clips 35 may also be used in the assembly. As shown in Fig. 3, these clips include, before being installed, a body section 36 and an upturned end flange 37.

Installation of the device is as follows: The upturned portion 22 of the clips 19 are nailed to the forms, previous to pouring the concrete, in alignment for the proper location of the reglet in

relation to the roof, these clips serving as the upper anchorage to hold open to the desired degree, the throat of the aperture or recess 11. The lower depending flange 18 of the reglet is also nailed in place to the forms to hold the same securely and to hold open the throat of said aperture or recess 11. The concrete is then poured and allowed to harden, after which the roofing is laid on the roof deck 33 with the edge portions 31 turned upwardly and in engagement with the adjacent vertical side of the wall 10.

Thereafter, the flashing is installed, the free edge of the top section 28 of the flashing being inserted into the recess 11 of the reglet, as shown in Fig. 2. The portions 22 of the clips 19 are then bent downwardly into engagement with the adjacent upper surface of the section 28 of the flashing, and the free ends 38 of said clips are turned about the adjacent edge 29 of the flashing, thereby securely fastening the flashing in place.

The downwardly projecting leg 26 of the flashing is normally inclined at a slight angle, as indicated at 39 in Fig. 4, and when installed the flashing is positioned in such a manner that the leg 26 is bent outwardly of the roofing material which it is holding in position, and due to the resiliency of the flashing strip the free edge of the lip 30 tightly engages the adjacent surface of the upturned edge 31 of said roofing, thereby forming a straight line water-tight seal.

If desired, the reinforcing clips 35 may also be used and, when installed at suitably spaced intervals, the flanges 37 of said clips are disposed behind the flange 16 of the reglet as shown in Fig. 2. The body portion 36 of the clips 35 engages the upper surface of the section 28 of the flashing, and the end portion 40 is turned about the edge 29 of said flashing to securely engage same.

I claim:

1. In a weatherproofing device: a reglet formed of sheet metal and having upper and lower walls defining a recess open at the outer side when installed; an inverted U-shaped portion at the inner side of the reglet; a flange depending from the upper wall of the recess and disposed across the upper outer side thereof, said flange having an inwardly and upwardly turned edge; a second flange depending from the lower wall of the recess in substantially the same plane as the first mentioned flange; a flashing member generally T-shaped in cross section and formed of resilient sheet metal, said flashing including a top section, an inturned portion extending beneath the top section but of less width than said top section, a depending leg having the free edge inclined relative to the plane of said leg for engagement with roofing material when installed, the top section of said flashing being insertable into the recess of the reglet; and clips having flanges secured between the sides of the inverted U-shaped portion and turned about the inturned portion of the flashing for securing the respective parts together.

2. The invention defined by claim 1, wherein there are also reinforcing clips having flanges insertable behind the first mentioned flange of the reglet and having an end portion turned about the inturned portion of the flashing.

3. In a weatherproofing device for installation in poured concrete walls of buildings having a roof deck covered with roofing material: a reglet of sheet metal secured in the concrete wall in upwardly spaced relation with the roof and having upper and lower walls defining a recess; a

6
10

flange extending downwardly from the outer edge of the upper wall and partially enclosing the recess along its outer side, said flange being substantially flush with the adjacent wall surface; a depending flange from the lower wall and substantially flush with the adjacent surface of the concrete wall; a flashing member generally T-shaped in cross section and formed of resilient sheet metal, said flashing including a top section, an inturned portion beneath the top section of less width than said section, and a downwardly extending leg and an inclined free edge portion; and means for securing the reglet and flashing together with the free edge of the flange of the leg engaging an edge portion of the roofing material, said leg being then placed under tension.

4. In a weatherproofing device: a reglet having upper and lower walls defining a recess open at one side, said reglet being formed of sheet metal; a flange depending from the upper wall across the upper portion of the open side of the recess; a second flange depending from the lower wall of the recess; a flashing member of resilient sheet material, said flashing member being generally T-shaped in cross section, the generally horizontal portion of said flashing member being insertable into the recess and being engageable with the edge of the first mentioned flange, and a free edge portion of the generally vertical part of the flashing member being turned from the major plane thereof; and means for securing a reglet and flashing member together, said means comprising a member anchored adjacent its inner end and having a portion turned about the outer edge of the generally horizontal portion of the flashing member.

5. In a weatherproofing device: a reglet having upper and lower walls defining a recess open at one side; an inverted U-shaped portion at the closed side of the reglet; a flange depending from the upper wall and closing the upper portion of the recess at its open side; a second flange depending from the lower wall of the recess; a flashing member having a portion insertable into the recess, and a depending leg; and means for securing the reglet and flashing together, said means comprising clips having flange portions secured between the legs of the inverted U-shaped portion of the reglet and having outer end portions bent about the outer edge of the flashing portion which is insertable into the recess.

6. In a weatherproofing device: a reglet formed of sheet metal and having upper and lower walls defining a recess open at the outer side when installed, an inverted U-shaped portion at the inner side of the reglet; a flange depending from the upper wall of the recess and disposed across the upper outer side thereof, said flange having an inwardly and upwardly turned edge; a second flange depending from the lower wall of the recess; a flashing member generally T-shaped in cross section and formed of resilient sheet metal, said flashing including a top section and a depending leg having the free edge inclined relative to the plane of said leg for engagement with roofing material when installed, the top section of said flashing being insertable into the recess of the reglet; and clips having flanges secured between the sides of the inverted U-shaped portion and turned about the outer edge portion of the flashing for securing the respective parts together.

7. In a weatherproofing device: a reglet formed of sheet metal and having upper and lower walls

defining a recess open at the outer side when installed; an inverted U-shaped portion at the inner side of the reglet; a flange depending from the upper wall of the recess and disposed across the upper outer side thereof, said flange having an inwardly and upwardly turned edge; a second flange depending from the lower wall of the recess; a flashing member generally T-shaped in cross section and formed of resilient sheet metal, said flashing including a top section, an inturned portion extending beneath the top section but of less width than said top section, a depending leg having the free edge inclined relative to the plane of said leg for engagement with roofing material when installed, the top section of said flashing being insertable into the recess of the reglet; clips having flanges secured between the sides of the inverted U-shaped portion and turned about the inturned portion of the flashing for securing the respective parts together.

8. In a weatherproofing device: a reglet formed of sheet metal and having upper and lower walls defining a recess open at the outer side when installed; an inverted U-shaped portion at the inner side of the reglet; a flange depending from the upper wall of the recess and disposed across the upper outer side thereof, said flange having

an inwardly and upwardly turned edge; a second flange depending from the lower wall of the recess in substantially the same plane as the first mentioned flange; a flashing member generally T-shaped in cross section and formed of resilient sheet metal, said flashing including a top section, and a depending leg having the free edge inclined relative to the plane of said leg for engagement with roofing material when installed, the top section of said flashing being insertable into the recess of the reglet; and clips having flanges secured between the sides of the inverted U-shaped portion and turned about the outer edge portion of the top section for securing the respective parts together.
